CLAIM

We claim the ornamental design for a buckle, as shown and described.

DESCRIPTION

FIG. 1 is a front perspective of a buckle;

FIG. 2 is a top plan view of a buckle;

FIG. 3 is a right elevational view of a buckle;

FIG. 4 is a left elevational view of a buckle;

FIG. 5 is a rear elevational view of a buckle; and,

FIG. 6 is a front elevational view of a buckle.

The dashed lines in the figures depict portions of buckle that form no part of the claimed design.
